DESIGN FOR A PIN CUSHION

Charles P. Englehardt, Far Rockaway, N. Y., assignor to Bassons, Maspeth, Long Island, New York, a copartnership

Application October 14, 1942, Serial No. 108,516

Term of patent 7 years

To all whom it may concern:

Be it known that I, Charles P. Englehardt, a citizen of the United States, residing at Far Rockaway, in the county of Queens and State of New York, have invented a new, original, and ornamental Design for a Pin Cushion, of which the following is a specification, reference being had to the accompanying drawing, forming a part thereof.

The dominant portion of the design resides in the portion shown in full lines.

I claim:

The ornamental design for a pin cushion, substantially as shown and described.

CHARLES P. ENGLEBARDT.
